SANDER PLATE ASSEMBLY FOR PORTABLE
SANDING TOOLSJoseph P. Yelpo, Greenville, S.C., and Joseph J. Romano,
South River, N.J., assignors to The Singer Company,
a corporation of New JerseyFiled Jan. 9, 1961, Ser. No. 81,588
1 Claim. (Cl. 51—189)

This invention relates to a sander plate assembly for a portable sanding tool and more particularly to means associated therewith for releasably clamping abrasive sheets.

It is an object of this invention to provide a sander plate assembly having simple but effective means for releasably clamping abrasive sheets.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawing,

FIG. 1 is a plan view of a sander plate embodying the invention.

FIG. 2 is an elevational view, partly in section, of the device of FIG. 1.

FIG. 3 is a fragmentary plan view of the device of FIG. 1 showing the parts in a specific operating condition.

FIG. 4 is an elevational view of the parts shown in FIG. 3.

FIG. 5 is an exploded view showing details of the cam and lever assembly.

Referring now to FIG. 1, a flat rectangular base 10 has struck-up lug portions 11 and 12 forming means for securing the base to a driving tool body (not shown). A rubber pad 13 is cemented to the bottom of the base 10 to serve as a cushion for an abrasive sheet which is releasably held against the pad 13 by means to be described.

At each end of the base 10 and secured to the top side thereof by means of rivets 15 is a leaf spring means 16 enlarged at the free end and bent to form a clamp portion 17. A transverse stiffening rib 18 is formed in the material in the clamp portion to provide lateral stiffness and a

2

central aperture 19 is provided, through which extends a lever-operated cam 20.

The cam 20, as best seen in FIG. 5, is preferably formed from a single piece by bending to provide a lever portion 21, a cam portion 22 and a body portion 23 which latter embraces a pin 24 secured to the base 10 as by riveting. The pin 24 stands with its axis positioned normally to the base 10 and extending upward through the central aperture 19 as shown.

In the position of the parts as shown in FIGS. 1 and 2, the leaf spring means 16 is normally warped to stand with the clamp portion 17 thereof spaced away from the base 10 to form a gap for insertion of the abrasive sheet 14. Clamping of the abrasive sheet is effected by rotation 15 of the lever-operated cam 20 about the pin 24 from the position shown in FIGS. 1 and 2 to the position shown in FIGS. 3 and 4. As the lever 21 is turned, the cam portion 22 first engages a depressed portion 25 of the leaf spring means. Further rotation of the lever 21 cams the clamp portion 17 of the leaf spring means 16 downward toward the base 10 until, in the position shown in FIGS. 3 and 4, the abrasive sheet 14 is securely but resiliently clamped between the clamp portion 17 and the base 10.

Removal of the abrasive sheet is effected by reversing the procedure described above.

Having thus set forth the nature of this invention, what we claim herein is:

A sander plate assembly for a portable sanding tool adapted to receive abrasive sheets comprising a base, leaf spring means secured at one end to said base and normally warped to stand at the other end with a clamp portion spaced away from said base to form a gap for insertion of said abrasive sheet, said leaf spring means having a centrally apertured portion, and lever-operated cam means positioned on said base to swing about an axis normal to said base and projecting through said apertured portion to urge said clamp portion to engage said abrasive sheet in clamping relation with the base.
